UNITED STATES PATENT OFFICE

CHARLES R. SCHENKEN, OF WASHINGTON, DISTRICT OF COLUMBIA

BOOKHOLDER

Application filed February 13, 1930. Serial No. 428,214.

My invention relates to hook holders, and more particularly to a device adapted to be fixed to a support and to a book to secure the book to the support and permit of ready opening and closing of the book.

Physical embodiments of my invention are especially adapted to use in connection with books of reference, such as telephone directories and the like, in public places where it is desirable to lock the books in place to prevent their unauthorized removal and at the same time permit the books to be easily and conveniently opened and closed.

Another object of my present invention is to provide a locking holder for a book which will maintain the book at all times in either of only two positions, first, the normally closed position, and secondly the open position, and which will prevent any displacement of the book except a minimum relative movement of the book and the support necessary to allow manipulation of the book from its closed to its open condition, and vice versa.

A further object is to provide a device of the character indicated which comprises a member secured to a support and another member fixed to the book, the two members being associated in hinged relation to allow the book to be opened and closed.

Another object is to provide means in the holder to support the book, when opened, in such a position that the book may be maintained open at any page and in such a way that the page at which the book is opened may be easily and conveniently read.

Another object is to provide a book holder having all the foregoing and other advantages which will be simple, efficient and durable in construction and which may be economically manufactured from a minimum of stamped sheet metal parts.

Further objects and advantages of my invention will be evident from a consideration of the accompanying drawings and the description hereinafter of the invention in one preferred form of embodiment.

In the drawings which form part of this application for Letters Patent and in which like reference characters indicate the same parts in the several views.

Figure 1 is a rear view in perspective of a book holder constructed according to the principles of my present invention applied to the covers of a book and ready to be secured to a suitable support;

Fig. 2 is a side elevational view of a book in closed position provided with a holder and secured to a support;

Fig. 3 is a cross sectional view through a book and support provided with a holder, the book being shown in open position;

Fig. 4 is a top plan view of the parts shown in Fig. 2;

Fig. 5 is a perspective view of that portion of my holder which is in practice applied to the book; and

Fig. 6 is a perspective view of that portion of my holder which is in practice secured to the support.

Referring now to the drawings, the reference numeral 1 designates any suitable base or support, and 2 indicates the side cover of a book. The support may be vertical, such as a wall, the side of a telephone booth or the like, or may be disposed in a horizontal or inclined plane, such as the top of a desk, table, book stand, etc., and may be formed of any well known wall or furniture material. Similarly, the book cover 2 may be of any size, material and construction, but is preferably a relatively stiff cover formed of boards. For the purposes of illustrating my present invention in one form of embodiment I have shown in the drawings a binder or supplemental cover detachably associated with a book by means of a book support made according to the teachings of United States Letters Patent No. 1,737,178, issued to me on November 26, 1929.

My present invention contemplates a pair of members 3, which will be hereinafter called the support members, adapted to be secured to the support, and a coacting pair of members 4 applied to the cover of the book and hereinafter called the book members. The connection between the members 3 and the support 1 may be immediate, as shown in the drawings, or if desired, the connection may be effected through the medium of an intermediate support pivotally asso-

iated with the support 1 to enable the closed book to be swung to and from parallel contacting relation with a wall. A convenient way of effecting connection between the members 3 and the support 1 consists in providing one end of each of the members with an angularly bent flange portion 5, apertured to receive screws, nails or the like; but it is to be understood that any effective type of connection is to be considered within the scope of my invention. In like manner, the members 4, which consist essentially of plates extending outwardly from the side covers of the book, may be secured to the book by any convenient means, such for example, as that shown in the drawings, where the members 4 are provided with integral lateral extensions 6 through which rivets or the like 7 are passed to fix the same firmly to the cover. This expedient is especially desirable since besides effecting connection between the cover 2 and the members 4, the extensions 6 serve in the use of the device an additional purpose which will presently be described.

Both the support and the book members are preferably formed of stamped or pressed comparatively rigid sheet metal. The essential parts of the support member 3 are a relatively narrow guide portion 8 and a relatively wide ear 9 which extends outwardly and is bent over from the guide portion 8. The cover member 4 is provided near its line of contact with the cover 2 with an aperture in the form of a slot 10 of a width and length just sufficient to receive the guide portion 8 of the support member, but insufficient to permit passage of the enlarged ear 9.

In assembling the elements of my present invention which have just been described, the members are associated in a manner which will be evident from Fig. 1 of the drawings, i. e., a pair of cover members 4 are first applied to the opposite side covers of a book, preferably about midway between the top and bottom, so that they extend from the cover adjacent to and parallel with the back of the book. The support contacting portion 5 of each one of a pair of support members 3 is then passed through the slot 10 of each of the book members 4 and fed through the slot until the guide portion 8 is received in the slot. With the book closed, as shown in Fig. 2, and the pair of guide portions disposed in substantial parallelism, the flanges 5 of the support members are secured to the support. The device is then in operative applied position.

Its method of use and operation is as follows:

When not in use the book is closed, as shown in Figs. 2 and 4, and pushed back between the guide portions 8 so that its back is disposed parallel with and adjacent to the surface of the support and both its covers are

substantially normal thereto. When the book is to be opened, it is slid outwardly from the support 1 between the guide portions 8 until further movement is prevented by contact of the members 4 with the ears 9, the extensions 6 preventing during this sliding operation marring of the leather or cloth cover material through contact with the support member. When the limit of its movement is reached the book is opened, assuming the position shown in Figs. 1 and 3, where the covers, or the extensions 6 of the cover member 4, contact with and are supported by the ears 9.

In order to cause the book to be disposed at such an angle when opened as will afford the maximum of convenience for reading, I prefer to form the ears 9 in non-parallel relation with the plane of the support, as best shown in Fig. 2. This may be accomplished by making the sides of the guide portions 8 non-vertical to the support, or by forming the line of the bend in the support member between the guide portion 8 and the ear 9 at an acute angle to the axis of the guide portion, or by a combination of both expedients. It should be noted that when the device is to be used with a vertical support it is desirable to dispose the guide portions 8 outwardly and upwardly at an oblique angle to the support, for the purpose of causing the book when closed to be urged by its own weight well back against the support.

I have illustrated and described my present invention in one preferred form of embodiment. Various modifications to meet varying conditions of use and preferences of the user will readily suggest themselves, but all such modifications, to the extent that they embody the spirit of the invention, are to be considered within the scope and purview of the appended claims.

Having thus described my invention what I claim and desire to secure by Letters Patent is:

1. A book holder including a pair of parallel guides secured to a support, means secured to the covers of a book and adapted to slide upon the guides when the book is closed and adapted to contact with the free ends of the guides when the book is opened.

2. A book holder including parallel guides each having one end secured to a support and a book supporting ear at its free end, in combination with means secured to the covers of a book adapted to slide upon the guides when the book is closed and to contact with the book supporting ears when the book is moved to the ends of the guides and opened.

3. A book holder comprising a pair of spaced guides having end portions adapted to be secured to a support, in combination with a pair of members secured to a book cover having ends adjacent the back of the book slidably engaged with the guides, and

means on the free ends of the guides and on the members respectively to limit relative movement of the guides and members.

4. A book holder comprising a pair of spaced guides each having one end adapted to be secured to a support and having its free end extending outwardly, in combination with a pair of plates secured to the book cover each having its rear end extending outwardly and provided with an aperture through which one of the guides is received.

5. A book holder comprising a pair of members each having means at one end for engagement with a support, means at the opposite end for supporting the book in opened position, and an intermediate guide portion, in combination with plates extending from the front and back covers of the book having slots receiving the intermediate guide portions of the members.

6. A book holder including parallel guides each having one end secured to a support and a book supporting ear at its free end of greater width than the parallel portions of the guides, in combination with means secured to the covers of a book adapted to slide upon the guides when the book is closed and to contact with the book supporting ears when the book is moved to the ends of the guides and opened.

30 7. A book holder including parallel guides each having one end secured to a support and a book supporting ear at its free end of greater width than the parallel portions of the guides and extending outwardly therefrom, in combination with means secured to the covers of a book adapted to slide upon the guides when the book is closed and to contact with the book supporting ears when the book is moved to the ends of the guides and opened.

40 8. A book holder including parallel guides each having one end secured to a support and a book supporting ear at its free end of greater width than the parallel portions of the guides and extending outwardly therefrom in a plane non-parallel to the plane of the support, in combination with means secured to the covers of a book adapted to slide upon the guides when the book is closed and to contact with the book supporting ears when the book is moved to the ends of the guides and opened.

50 9. A book holder comprising a pair of support members having guide portions, means at one end of the members adapted to be secured to a vertical support whereby the axes of the guide portions are disposed outwardly and upwardly from the support and substantially parallel with each other, in combination with members associated with the covers of a book slidably engaged with the guide portions.

60 10. A book holder according to claim 9, in which the free ends of the support members are provided with enlargements to limit

relative movement of the support members and the book cover members.

11. A book holder according to claim 9, in which the free ends of the support members are provided with ears of greater width than the guide portions and extending outwardly therefrom to limit relative movement of the support members and the book cover members and to support the book when opened at the outer limit of its movement.

70 12. A book holder according to claim 9, in which the free ends of the support members are provided with outwardly extending ears of greater width than the guide portions and non-parallel to the support to limit relative movement of the support members and the book cover members and to support the book at an angle to the vertical when opened at the outer limit of its movement.

80 In testimony whereof I affix my signature.

CHARLES R. SCHENKEN.
